(57) **CLAIM**

The ornamental design for a cradle for terminal for managing selling information, as shown and described.

DESCRIPTION

FIG. 1 is a perspective view of a cradle for terminal for managing selling information showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is an top plan view thereof; and,

FIG. 7 is an bottom plan view thereof.

All broken dashed and dotted lines in the drawings depict portions of the cradle for terminal for managing selling information that form no part of the claimed design.

1 Claim, 7 Drawing Sheets
